MULTICOLOR PRINTING MACHINE

Adolph M. Zuckerman, New York, N. Y., assignor
to R. Hoe & Co., Inc., New York, N. Y., a corporation of New York

Application June 2, 1942, Serial No. 445,420

7 Claims. (Cl. 101—180)

This invention relates to multicolor web printing machines and more particularly to improvements in such printing machines wherein means is provided to dry the ink after printing, by heating and subsequently cooling the web.

In high speed printing machines used for multicolor printing, which have ink drying means incorporated in their structure, it is desirable that the amount of space required for the installation be kept to a minimum. It is also desirable that the printed web be guided in such a manner that freshly printed areas thereon will not engage any part of the machine until the ink has been dried, to prevent "smutting" of the freshly applied ink.

It is often desirable in machines of this kind to print the web with several different colored inks superimposed upon the same surface, and to do this without running the machine at a slower speed than that at which it would be run to print in one or two colors.

One object of this invention is to provide a web printing machine including ink drying devices, that will print and dry one or two webs with either one or two kinds of ink at high speed, or alternatively, will print and dry one web with either three or four kinds of ink at the same high speed.

Another object is to provide a printing machine arranged to operate on a web that is led through a first printing unit and an ink drying device, and then through a second printing unit and an ink drying device, to complete the printing on both sides of the web when applying one or two colors on each side, or alternatively to lead a web successively through two printing units and two drying devices and then through a second pair of printing units and two drying devices to apply three or four colors on each side, the web speed in either case being the same.

Still another object of the invention is to provide a web printing machine having improved means for preventing the freshly printed surface of a web printed successively by a plurality of printing units, from coming into contact with parts of the machine, while it is passing from one printing unit to the next unit.

It is also an object of this invention to provide a multicolor printing machine of generally improved construction, that will be simple, durable and relatively inexpensive in construction, as well as convenient, practical, serviceable and efficient in use.

With the foregoing and other objects in view, which will appear from the description, the in-

vention resides in the combination and arrangement of parts, and in the details of construction hereinafter described and claimed, it being understood that various changes in the precise embodiment of the invention herein disclosed may be made within the scope of what is claimed and without departing from the spirit of the invention.

A preferred embodiment of the invention is illustrated in the accompanying drawings, wherein:

Figure 1 is a diagrammatic illustration showing a side view of a printing machine made in accordance with the invention and shown as adapted to print and dry one or two webs with either one or two kinds of ink on each side thereof;

Figure 1A illustrates the same machine shown as adapted to print and dry a web with either three or four kinds of ink on each side thereof;

Figure 2 is a side view of a web carrier over which a freshly printed web having margin spaces may be led, and which is adapted to maintain the freshly printed surface of the web out of contact therewith;

Figure 3 is an enlarged and broken longitudinal sectional view of the web carrier shown in Figure 2, as seen on the line 3—3 of Figure 2 and looking in the direction of the arrows;

Figure 4 is a cross sectional view of the web carrier shown in Figures 2 and 3, as seen on the line 4—4 of Figure 3 and looking in the direction of the arrows;

Figure 5 is a broken longitudinal sectional view of a web carrier over which a freshly printed web having no margin spaces may be led, and which also is adapted to maintain the freshly printed surface of the web out of contact therewith; and

Figure 6 is a cross sectional view of the web carrier shown in Figure 5, as seen on the line 6—6 of Figure 5 and looking in the direction of the arrows.

The printing machine, shown in Figure 1 includes a plurality of printing units 11, 12, 13 and 14 and ink drying devices 15, 16, 17 and 18. As herein shown the printing unit 11 is superimposed over the unit 12, the unit 13 over the unit 14, the ink drier 15 over the drier 16, and the ink dryer 17 over the dryer 18. Each of the dryers 15, 16, 17 and 18 has in its structure heating units of known form and of sufficient heat radiating capacity to efficiently dry the ink applied upon a web by one of the printing units 11, 12, 13 or 14, when this web is being fed at relatively high speed. Each of the printing units shown includes

an impression cylinder 21 and plate cylinders 22 and 23 cooperating with the impression cylinder 21. Suitable knowninking mechanisms 24 and 25 are provided, one for each of the plate cylinders 22 and 23, and by each of these, ink of the desired color is transferred from fountains 26 and 27 respectively to printing plates on the plate cylinders.

As shown in Figure 1, the printing machine herein illustrated is adapted to print two colors or kinds of ink on each side of two webs 28 and 29, the web 28 being fed in sequence through the printing unit 11, the ink dryer 15, the unit 13, and the dryer 17, and the web 29 being fed in sequence through the printing unit 12, the ink dryer 16, the unit 14, and the dryer 18. Web guiding members, herein designated web carriers 30 and 31, function similarly to guide rollers, in that they act to guide a web, but as will be hereinafter explained, they are arranged to prevent contact with the adjacent face of a web passing around them. In its passage to the unit 11 from a source of supply, the web 28 is guided by web carriers 30 and 31, and in its passage from the unit 11 to the unit 13, it is guided by rollers 32 and 33 to the casing 34 of the ink dryer 15, and then over a guide roller 35, cooling rollers 36 and 37, and rollers 38, 39, 41, 42, 43 and 44 (the roller 43 preferably being a "compensator" roller which is made adjustable to effect register of the printing). From the unit 13, the web 28 is guided by a web carrier 45, and a guide roller 46, to the casing 47 of the dryer 17 from which it is led over a roller 48, cooling rollers 49 and 51 and rollers 52, 53, and 54 to the usual folding and delivery mechanism (not shown).

In its passage to the unit 12 from a source of supply, the web 29 is led over guide rollers 55 and 56, and in its passage from the unit 12 to the unit 14, it is led over a web carrier 57 and a guide roller 58 to the casing 59 of the dryer 16 from which it is led over a guide roller 60, cooling rollers 61 and 62, guide rollers 63, 64, 65 and 66, a compensator roller 67, and a web carrier 68. After leaving the unit 14, the web 29 is guided by rollers 69 and 71 to the casing 72 of the dryer 18, from which it is led over a roller 73, cooling rollers 74 and 75, and rollers 76, 77 and 78 to the usual folding and delivery mechanisms (not shown). Each of the dryers 15, 16, 17 and 18 has sufficient drying capacity to properly dry impressions of two colors while the press is being run at maximum speed.

In mounting the pairs of the dryers 15, 16 and 17, 18, it is preferable to mount them tilted slightly from a vertical line, in order that the rollers 58 and 46 may be effective to hold the web in proper alignment, and thereby prevent injury to the web or to the printing, while it is passing through the dryers. This is especially important with the web runs shown in Figure 1A.

It will be understood that all of the cylinders, rollers, and web carriers are supported by and extend between spaced apart machine side frames 79. The ink dryers 15, 16, 17 and 18 are mounted between these frames in the available space, one dryer between the units 11 and 13, another between units 12 and 14, and two dryers between the units 13 and 14 and the folding and delivery mechanism.

The printing machine herein disclosed is also adapted to print and dry a single web, printed with either three or four kinds of ink on each side while running at the same high speed as when

printing with one or two colors. This adaptation is shown in Figure 1A, wherein a web 82 enters the machine from a usual source of supply (not shown), and is led over guide rollers 55 and 56 into the printing unit 12 to have one or two colors printed on its surface A. It is then led over the web carrier 57, a compensator roller 61, web carriers 30 and 31 to the unit 11 to have one or two more colors printed upon its surface 10 A. From the unit 11 the web is guided by the rollers 32 and 33 into the casing of the dryer 15, through which it is guided by the roller 35 and from which it is guided by the roller 58 into the casing 59 of the dryer 16.

From the dryer 16, the web 82 is led over the roller 60, the cooling rollers 61 and 62, the rollers 63, 64, 65, 39, 41 and 42, the compensator roller 43, and guide roller 44 into the printing unit 13, to have one or two colors printed upon its surface 20 B. After leaving the unit 13, the web is led over the web carrier 45, the compensator 67 and the web carrier 68, to the printing unit 14 to have one or two more colors printed on its surface B. From the unit 14, the web 82 is guided by the rollers 69 and 71 into the casing 72 of the dryer 18 through which it is guided by the roller 73, and from which it is guided by the roller 46 into the casing 47 of the dryer 17. Upon leaving the dryer 17, the web 82 passes over the roller 48 and the cooling rollers 49 and 51, and is then guided by the rollers 52, 53 and 54 toward the usual folding and delivery mechanism (not shown).

In passing between the units 12 and 11, the 35 web 82 is led over the web carriers 57, 30 and 31, and in passing between the units 13 and 14 it is led over the web carriers 45 and 68 with the freshly printed surfaces A and B facing the web carriers. It will be understood that if ordinary 40 guide rollers were used at these points, the fresh ink might offset onto the rollers and "smut" the web or otherwise detract from the quality of the printing, and hence it is desirable to provide means to prevent all freshly printed portions of 45 the web from coming into contact with the means employed to guide the web as it is led from one printing unit to the other. In machines for producing work having margin spaces between 50 pages on the web, the web carriers 30, 31, 45, 57 and 68 are formed as illustrated in Figures 2, 3 and 4, but in machines producing work having no margin spaces, these web carriers are formed as 55 illustrated in Figures 5 and 6. The web carrier shown in Figures 2, 3 and 4 includes a plurality of hollow cylinders 91, one for each page being printed widthwise of the web. These cylinders, as herein shown, are secured on a fixed shaft 92 and cooperate with intermediate web supporting members 93, and end web supporting mem- 60 bers 94.

The members 93 and 94 are identical, and each cooperates with an inner ring 95 tightly mounted on a hub 96 formed integral with one of the adjacent cylinders 91. The members 93 and 94 are 65 freely rotatable, being supported from the inner rings 95 by balls 98, and may be ball bearings of a width somewhat less than the width of the margin spaces between the pages being printed. The diameter of the cylinders 91 is slightly smaller 70 than the diameter of the members 93 and 94, whereby a web led thereover, will engage only the peripheries of the members 93 and 94 and will be slightly spaced from the surface of the non-rotating cylinders 91.

In order to prevent the web, when under ten-

sion, from being drawn into contact with the surfaces of the cylinders 91, they are each provided with a plurality of holes 99 located in those portions that are covered by the web. The holes 99 extend through the shell of the cylinders 91 to the hollow interior 100, and it will be seen that air under pressure in the interior of the cylinders 91 presses upon the underside of the web and prevents it from being drawn down into contact with the cylinder. Each of the cylinders 91 has an air inlet pipe 101 through which air under pressure may be supplied thereto from a suitable source (not shown).

The alternative form of web carrier shown in Figures 5 and 6 includes a roller having a cylindrical shell 102 which is provided with a plurality of holes 103 over its entire periphery. These holes extend through the shell 102 to the hollow interior 104. The cylindrical shell 102 has shaft ends 105 and 106, that are journaled in the side frames 79 of the machine. One of the shaft ends 105, is provided with a bore 107 communicating with the interior of the shell through which air under pressure may be supplied, to prevent the web from being drawn tightly against the periphery of the shell.

In order that the holes 103 in that portion of the shell that is not covered by the web may be otherwise covered, to prevent the wasteful escape of air, a shield 108 is supported upon a shaft 109 in position to extend along and partially surround the shell 102 at the side opposite from the web, and is fitted closely to the periphery of the shell. The shield 108 effectively blocks the passage of air from the shell 102 except at the web covered portion thereof, where if under sufficient pressure, the air will lift the web sufficiently to escape between the shell and the web. If desired the shaft 109 may be made adjustable about the shaft ends 105 and 106 to permit the shield 108 to be adjusted about the shell 102.

From the foregoing description of the paths followed by the webs passing through the machine, it will be noted that when the printing on one side of a web is completed by one printing unit, the web is then carried through only one of the drying units, before being printed on the other side or folded, but when a web is carried through two printing units to complete the printing on one side, it is then carried through two drying units successively, thus providing twice the drying capacity for work having impressions in four colors, that is provided for work having impressions in two colors. By the arrangement shown, it is possible to use the drying equipment in a most efficient manner.

It will be seen that a printing machine arranged as depicted may be operated to print either one or two webs with one or two kinds of ink on one or two sides of the web, and the ink thoroughly dried while the machine is running at high speed, and alternatively, one web may be printed with either three or four kinds of ink and thoroughly dried when running the machine at equally high speed. Also, operation of the drying equipment under either of the alternative conditions is at the highest efficiency, and the machine is relatively small and compact, with consequent reduction in cost and space occupied.

It will be understood that the invention may be embodied in other specific forms without departing from the spirit or essential attributes thereof, and it is therefore desired that the present embodiment be considered in all respects as 75

illustrative and not restrictive, reference being had to the claims rather than to the foregoing description to indicate the scope of the invention.

What I claim is:

1. In a multicolor web printing machine, a first group of printing units, a second group of printing units arranged in line with the first, a first group of ink dryers operably interposed between the first and second group of printing units, a second group of ink dryers operably following the second group of printing units, means for leading a web of a first web run through a printing unit of the first group, through a dryer of the first group, through a printing unit of the second group and through a dryer of the second group and simultaneously leading a web of a second web run through a printing unit of the first group, through a dryer of the first group, through a printing unit of the second group and through a dryer of the second group, and means for alternatively leading a web of a third web run successively through the printing units of the first group, successively through the ink dryers of the first group, successively through the printing units of the second group, and successively through the ink dryers of the second group, the ink dryers of each group being so arranged that the web is led in a direct path through and between them.
2. In a multicolor web printing machine, a first group of printing units, a second group of printing units arranged in line with the first, a first group of ink dryers operably interposed between the first and second group of printing units, a second group of ink dryers operably following the second group of printing units, means for leading a web of a first web run through a printing unit of the first group, through a dryer of the first group, through a printing unit of the second group and through a dryer of the second group and simultaneously leading a web of a second web run through a printing unit of the first group, through a dryer of the first group, through a printing unit of the second group and through a dryer of the second group, means for alternatively leading a web of a third web run successively through the printing units of the first group, successively through the ink dryers of the first group, successively through the printing units of the second group and successively through the ink dryers of the second group, the ink dryers of each group being so arranged that the web is led in a direct path through and between them, and a web carrier running in contact with the freshly printed side of the web as it passes from one printing unit to another printing unit in the third web run, the said web carrier being provided with members which engage a relatively small area of the web and means for preventing contact of the major portion of the web with the web carrier including means for directing a current of air between the major portion of the web and the web carrier.
3. A web carrier for guiding a web in a printing machine, comprising a shaft, a plurality of non-rotatable hollow cylinders aligned on the shaft and having peripheral walls and closed ends, and web-engaging rollers rotatably supported on aligned bearing members, one at each end of each cylinder, the rollers being slightly larger in diameter than the cylinders, and each of the cylinders being independently connected with a source of air under pressure and having holes through the portion of its peripheral wall

that is covered by the web, whereby air under pressure in the cylinders may pass through and hold the web out of contact with the surface of the cylinder.

4. In a multicolor web printing machine having printing units and ink drying units arranged in two tiers, a lower tier comprising in sequential arrangement, a first printing unit, a first drying unit, a second printing unit and a second drying unit, and an upper tier positioned over the lower tier and comprising in sequential arrangement, a first printing unit, a first drying unit, a second printing unit and a second drying unit, and web carriers having means to guide webs without contacting their printed areas, whereby a first and a second web may be printed first one one side and then on the other side, by leading the first web successively through the first printing unit, the first drying unit, the second printing unit and the second drying unit of the lower tier, and the second web successively through the first printing unit, the first drying unit, the second printing unit and the second drying unit of the upper tier, and alternatively a single web may be printed on each side by leading it successively through the first printing unit of the lower tier, about a web carrier, through the first printing unit of the upper tier, the first drying unit of the upper tier, the first drying unit of the lower tier, the second printing unit of the upper tier, about another web carrier, through the second printing unit of the lower tier, the second drying unit of the lower tier, and the second drying unit of the upper tier.

5. In a multicolor web printing machine, a plurality of printing units, a plurality of ink drying units, a plurality of web carriers having means to guide a web without engaging its printed area, means to print and dry ink on two webs, each web being printed and dried on one side by leading it successively through a printing unit and a drying unit, and then printed and dried on the other side by leading it successively through another printing unit and another drying unit, the two webs then being associated and led to a delivery mechanism; and alternatively to print and dry ink on a single web by leading it successively through one of the said printing units,

about a web carrier, through another of the said printing units, and through two of the said drying units to print and dry one side of the web, and then successively through another of the said printing units, about a web carrier, through still another of the said printing units and through two other of the said drying units to print and dry the other side of the single web which is then led to a delivery mechanism.

10 6. In a multicolor web printing machine, upper and lower printing units, upper and lower ink drying units, and a plurality of web carriers having means to guide a web without contacting its printed area, the said printing units, ink drying units and web carriers being arranged in such relation that two webs may be printed and dried by leading each web upward through a printing unit, downward through a drying unit, downward through another printing unit, and upward through another drying unit, and the other web may be printed by leading it upward through another printing unit, downward through another drying unit, downward through another printing unit, and upward through another drying unit; and alternatively, a single web may be printed by leading it upward through a printing unit, about a web carrier, upward through another printing unit, downward first through one and then through another ink drying unit, downward through another printing unit, about another web carrier, and downward through another printing unit, and upward first through one and then through another ink drying unit.

15 7. A web carrier for guiding a web in a printing machine comprising a shaft, a plurality of bearings each having a cylindrical inner member and a cylindrical outer member, and a plurality of non-rotatable hollow cylinders having peripheral walls slightly less in diameter than the peripheries of the outer bearing members, and having end caps with hubs, the periphery of each hub being fitted to the inner member of a bearing and each of the cylinders being independently connected with a source of air under pressure and having holes through the portion of its peripheral wall that is covered by the web.

ADOLPH M. ZUCKERMAN.
